UNITED STATES PATENT OFFICE

CHARLES L. DEPOLLIER, OF BROOKLYN, NEW YORK.

DESIGN FOR A WATCH-BOW.

SPECIFICATION forming part of Design No. 24,398, dated June 18, 1895.

Application filed April 17, 1895. Serial No. 546,134. Term of patent 7 years.

To all whom it may concern:

Be it known that I, CHARLES L. DEPOLLIER, a citizen of the United States, residing in Brooklyn, in the county of Kings and State of New York, have invented and produced a new and original Design for Watch-Bows, of which the following is a specification, reference being had to the accompanying drawings, showing the ornamentation applied to a

10 watch-bow of the antique shape or pattern.

In the accompanying drawings, Figure 1 is a side view of a watch-bow having the ornamentation applied thereto. Fig. 2 is an edge view thereof.

15 The leading feature of my design consists in the raised or beaded sides of the bow, the outer edge or periphery of the same being

left clean or smooth. These beads which are lettered A are larger in the center, and decrease in size as they approach the ends of 20 the bow B, where the latter enters the pendant C of the watch case, said beads or raised portions being of such size, or raised to that extent, as to correspond to the beaded portion or design of the watch case, of which it forms 25 a portion.

What I claim is—

The design for a watch case bow as hereinabove shown and described.

CHARLES L. DEPOLLIER.
